UNITED STATES PATENT OFFICE.

JOHN S. S. FULTON, OF NEW YORK, N. Y., ASSIGNOR TO ELIAS T. JESTER, TRUSTEE.

CULM-BURNING FURNACE.

1,130,389.

Specification of Letters Patent.

Patented Mar. 2, 1915.

Application filed March 31, 1911. Serial No. 618,152.

To all whom it may concern:

Be it known that I, JOHN S. S. FULTON, of the city of New York and State of New York, have invented certain new and useful improvements in Culm-Burning Furnaces; and I do hereby declare the following to be a full, clear, and exact description of the invention, such as will enable others skilled in the art to which it appertains to make and use the same.

In the use of anthracite culm as fuel for boiler or other furnaces, it is essential that sufficient air be injected into the charge of fuel; that this air shall be properly proportioned and heated before its union with the fuel at least to the temperature required for the ignition of the fuel; and that the combined air blast and fuel be so introduced into the previously heated furnace that the fuel will be held in suspension until its complete combustion has taken place before it can reach and collect upon the bottom or other surface of the furnace. When pulverulent anthracite fuel becomes lodged on a surface its combustion ceases; it rapidly accumulates and the collection soon becomes carbonized, choking up the passage way for the gases so that the furnace is rendered inoperative.

My invention contemplates an improved culm burning furnace adapted to insure the attainment of the objects above specified.

It is well known in the art that while pulverized coal or other fuel of a gaseous or volatile nature, such as bituminous coal, will burn readily in furnaces adapted for that purpose, yet for the combustion of finely powdered anthracite coal, which is extremely low in volatile or gaseous matter, special designs of furnaces must be employed. They must be capable of attaining a maximum degree of heat owing to the fact that culm or powdered anthracite is not only difficult to ignite, but burns very slowly after ignition as compared with powdered bituminous coal. Consequently, an efficient culm burning furnace should be designed for the purpose of sustaining the powdered fuel in suspension sufficiently long to insure complete combustion, for maintaining maximum temperature and for supplying sufficient air and preheating the same to a temperature equal to or greater than that required for the ignition of the fuel.

My invention is illustrated in the accompanying drawing in which—

Figure 1 is a vertical longitudinal sectional view and Fig. 2 a horizontal sectional view on line 2—2, Fig. 1.

Referring to the drawing, the furnace 1 is preferably of cylindrical shape and constructed with an inner wall 2 and an outer wall 3, the wall 2 inclosing the combustion chamber 4. The walls 2 and 3 are separated to provide an air passage 5. The top or cover 6 completes the inclosure of the combustion chamber and this top as well as the inner wall are preferably built of fire brick.

Atmospheric air is admitted to the space 5 through ports 7 closed by adjustable covers 8. The ports 7 are preferably at or near the bottom of the furnace on opposite sides of the flue or passage 9 leading from the combustion chamber to the boiler 10, the object being to locate these as far as possible from the actual zone of combustion. The port establishing communication between the air space 5 and the combustion chamber 4 is shown at or near the top of the furnace and is designated by the numeral 12. By reference to Fig. 2, it will be noted that this port is formed tangentially with relation to the cylindrical formation of the combustion chamber, so that the air passing through the port will be caused to whirl about in the combustion chamber.

At 14, Fig. 1, I have shown a fuel hopper equipped with a conventional form of feeding means 15, adapted for feeding finely pulverized fuel. Any of the well known pulverizing mills are adapted for the purpose. From the hopper 14 the fuel passes through a charging spout 16 in the top 6 of the furnace and is introduced into the top of the combustion chamber at a point directly in line with the port 12 so that the charge of fuel will encounter the air supply at the moment of its entrance into the combustion chamber.

In Fig. 2 I have shown at 17 a valve controlled pipe leading from any source of supply and having its nozzle projected through the outer wall 3 of the furnace and in alignment with the port 12. Adjacent this pipe the wall 3 is formed with an opening 18 covered by a plug 19 through which a torch may be inserted to ignite the charge of oil fuel supply through pipe 17 at the com-

mencement of the process, should it be preferred to heat the furnace with oil instead of wood or other fuel. I have shown the furnace provided with a cleanout passage 20 5 equipped with a door 21.

In operation the dampers 3 are adjusted to admit a supply of air to the space 5. I 10 preferably use oil fuel to heat the furnace, although this may be accomplished by a wood fire, the fuel being introduced through passage 20. When oil is used it is supplied to the combustion chamber through pipe 17 and is immediately ignited by a torch, the fuel being preferably under pressure. The 15 use of this oil fuel is continued until the walls 2 of the combustion chamber are heated to a red heat. The supply of oil fuel is then discontinued and steam pressure is supplied through pipe 17 simultaneously 20 with the feed of fuel, thus injecting the air from the passage 5 into the column of fuel falling from the hopper 14. It will be noted that as the fuel enters the combustion chamber at 16 it encounters the supply of 25 highly heated air from space 5 and the combined charge of fuel and heated air is forced by the pressure to whirl about in the top of the combustion chamber, thus prolonging the distance the fuel must travel in its fall 30 to the bottom of the furnace. This has been found sufficient to insure complete combustion before it can reach and lodge upon the furnace bottom.

It is well known that a powdered fuel, for 35 the combustion of which my furnace is adapted, is very buoyant, but not sufficiently so to prevent its rapid fall to the bottom of a combustion chamber into the top of which it has been introduced. In the present in- 40 stance, however, the intense heat within the combustion chamber rises toward the top of the latter, and in so doing its buoyant force aids the whirling action of the air blast in maintaining the fuel in suspension suffi- 45 ciently long to effect thorough combustion.

I am aware of prior constructions, intended for the combustion of powdered fuel, consisting of a vertically disposed furnace into the top of which the fuel and air are 50 introduced; but so far as I know all such structures have simply contemplated an air supply passing upward beside the furnace and over the top thereof and downward into the furnace, the fuel being fed down- 55 ward in line with the center of the furnace. Practice has demonstrated that such structures will not effect the combustion of anthracite culm, primarily because the air, instead of being intimately associated with 60 the fuel, tends to pass down into the furnace against the walls thereof. I have found it essential to thoroughly mix the air and fuel immediately upon entering the

furnace and that the air should be forced by pressure and intersect the fuel feed, that is, 65 enter the furnace in a line of direction which crosses that of the fuel and that the results are greatly aided if the fuel and air be whirled about in the furnace.

I claim as my invention:—

1. In a culm burning furnace, the combination with a vertically disposed combustion chamber and means for supplying powdered fuel at the top thereof, and permitting it to gravitate therein, of a preheated atmospheric air supply leading from a point remote from said combustion chamber and passing adjacent the latter throughout its length, and entering its top so as to intersect the gravitating column of fuel supply, 75 and means for accelerating the preheated air at its point of union with the fuel.

2. In a culm burning furnace, in combination, a vertically disposed combustion chamber having two walls separated to provide an intermediate air space, means for introducing atmospheric air to said space at or near the bottom of said combustion chamber, and means for regulating said air supply, the inner wall of said combustion chamber being formed with a horizontal port at 85 its top establishing communication between said air space and the interior of said combustion chamber, and means for supplying fuel to said combustion chamber through 90 the top thereof and allowing it to gravitate therein in line with said port.

3. In a culm burning furnace, a combustion chamber in communication with a boiler fire box, an atmospheric air supply 100 entering said furnace at or near the bottom thereof on opposite sides of the fuel leading from said combustion chamber to said fire box and entering said combustion chamber near the top thereof, and means for supplying a gravitating column of fuel to said combustion chamber through the top thereof or near the point of entrance of said air supply.

4. In a culm burning furnace, a cylindrical combustion chamber having two walls separated to provide an intermediate air space, the inner wall having a port leading from said air space to the interior of said combustion chamber in a tangential direction, and the outer wall having a fluid pipe in line with said port, and a torch opening adjacent said fluid pipe, and means for supplying fuel to said combustion chamber.

In testimony whereof, I have signed this 120 specification in the presence of two subscribing witnesses.

JNO. S. S. FULTON.
